UNITED STATES PATENT OFFICE.

SVEN T. NELSON, OF CHICAGO, ILLINOIS, ASSIGNOR TO SULLIVAN MACHINERY COMPANY, A CORPORATION OF MASSACHUSETTS.

FURNACE.

Application filed October 31, 1921. Serial No. 511,900.

My invention relates to furnaces, and more particularly to blank heating furnaces for heating blanks preliminary to forging operations.

5 An object of my invention is to provide an improved furnace. Another object of my invention is to provide an improved heating furnace for the heating of continuous series of blanks for use in forging machines. A 10 further object of my invention is to provide an improved heating furnace having means whereby blanks may be automatically fed through the furnace and discharged when heated to the desired temperature. Other 15 objects and advantages of my invention will hereinafter more fully appear.

In the accompanying drawings I have shown for purposes of illustration one form which my invention may assume in practice.

20 In these drawings,—

Fig. 1 is a plan view, partially broken away, of the illustrative form of my improved furnace.

Fig. 2 is a front elevation thereof.

25 Fig. 3 is a vertical section on a plane corresponding to the line 3—3 of Fig. 2.

Fig. 4 is a series of views showing the furnace charging device.

It is now a well known fact that the cutter bits employed with cutter chains of coal mining machines may be advantageously and cheaply made up by automatic forging machines. It is also common to other manufacturing processes to forge shapes from 35 heated blanks. For the purpose of providing these heated blanks continuously and at suitable intervals for their most advantageous treatment, I have devised the invention whose illustrative form I now describe.

40 In its illustrative form my invention comprises a heating furnace generally designated 1 and automatic blank discharging means generally designated 2. The furnace 1 together with the blank discharging means 2 is mounted upon a suitable frame generally indicated by 3 having supporting legs 4. Immediately upon the top of the frame is mounted a metal housing 5 of a general rectangular shape in horizontal section and somewhat wider at the top than the bottom when viewed from one side. This housing is lined on the top, bottom, sides and back with fire brick, all joints being luted with fire clay. In the front wall 45 of the furnace there are arranged one or

more oil burners, three of these being shown in the present drawings and designated 6, although it will be obvious that depending upon the number of the bits to be heated and the time which may be devoted to the 60 heating of the bits, there may be a wide variation in the number of burners necessary.

Spaced between the burners 6 within the casing of the furnace and projecting from the front wall 7 thereof are a series of guide 65 ribs 8 which are spaced apart by short distances in such manner as to provide guideways for the blanks to be heated, while wider spaces separate the several guideways, and through these wider spaces the burners 70 discharge and the remaining space is filled up with fire brick or fire clay as indicated at 9 to protect the guide ribs 8 and the front wall of the furnace. Arranged in the top of the furnace are a series of feed slots 10, 75 11, 12 and 13, which slots are in alinement with the channels formed between the guides 8 in which the blanks are to be guided during heating. As illustrated in Fig. 3, bits dropped in through the feeding slots remain 80 superimposed one upon another between the guides 8 and are gradually fed down on operation of the discharging means by gravity as later described. It will also be evident that one or more stacks of blanks herein in 85 the form of bits may be provided in the furnace and that the furnace may be designed to accommodate as many stacks as desired. Herein it will be noted from Fig. 1 that the blanks are in part protected by 90 the guides from the direct heat of the combustion chamber, and as a result only the projecting portions, which will be the portions to be worked, will be heated up to the highest temperature.

95 For the purpose of permitting the loading of the furnace for the first time I employ a magazine member 17 which is U-shaped in cross section except at the bottom where it is rectangular as indicated at 18. Across 100 the bottom of this member lies a pin 19 having a hooked end 20 which may be engaged by means inserted through any of the discharge slots 21, later described, arranged below and in alinement with the bottoms of 105 the stacks of bits. The magazine member 17 is filled with blanks and is then inserted through one of the charging slots 10, 11, 12 or 13. When this magazine member is resting upon the bottom of the furnace opposite 110

one of the discharge slots 21 which are provided in the front wall, the pin 20 may be withdrawn and the bits will then completely fill one of the guideways between the members 8. Thereafter the magazine member 17 is withdrawn and, during the operation of the furnace, bits are fed into the various feed slots as rapidly as they are discharged through the discharge slots 21.

10 The bottom of the furnace is provided with a water jacket 22 and in the upper surface of the water jacket, i. e. in the bottom plate of the furnace there are formed guideways 23 in which are reciprocable plungers or ejectors 24 each adapted to engage the bottom bit in its respective stack and force it out through the respective discharge opening 21. These rods are reciprocated by pitmans 25 pivoted to crank disks 26 and rotatable by means of shafts 27 driven by gears 28 in bearings 29. A common driving shaft 30 having pinions 31 thereon drives the gears 28 and consequently the period between the discharge 25 of blanks from the several stacks may be made uniform and may be adjusted as desired by varying the rate at which the shaft 30 rotates. It will be observed that the rods 24, being surrounded on three sides 30 by water cooled walls, are prevented from overheating and that the direct access of heat from the furnace to their upper sides is prevented by the lining of fire brick on the bottom of the furnace.

35 From the foregoing description the mode of operation of this improved bit heating mechanism will already be apparent. Let it be assumed that the several stacks of bits are already in position and that the furnace 40 has been heated up to the desired temperature and the bits likewise brought to the temperature which is desired. Then by driving the shaft 30 by means of the pulley shown thereon it will be possible successively to discharge these blanks and if unheated blanks are continuously supplied through the slots 10, etc., as blanks are discharged heated through the discharge openings 21, the operation of the furnace 45 will evidently be continuous. It will be understood that either oil fuel or gas of any description can be used with the furnace and that the mechanism may be operated by an electric motor or in any other suitable way provided adjustment of the timing is made possible. It will also be noted that the furnace heating chamber is 50 open only through the two flues 32 at the top thereof and so that the heat is concentrated in a very efficient manner.

55 While I have in this application specifically described one form which my invention may assume in practice, it will be understood that this form of the same is 60 shown for purposes of illustration and that

the invention may be modified and embodied in various other forms without departing from its spirit or the scope of the appended claims.

What I claim as new and desire to secure 70 by Letters Patent is:

1. In a blank heating furnace, a combustion chamber, parallel blank guiding means in said chamber to receive and guide a series of blanks during their passage 75 through the chamber, said guides having surfaces contacting with said blanks to cover a substantial portion of said blanks but to have the portions to be worked projecting into the chamber whereby the portions of the blanks to be worked may be heated to a much higher temperature than the protected portions, and means for 80 serially discharging the blanks.

2. In a blank heating furnace, a heating 85 chamber, parallel blank guides formed therein each being adapted to receive a stack of superimposed blanks, means to feed the blanks in said guides through openings formed in the top of said chamber, and means including reciprocating rams movable in a plane perpendicular to said guides to successively engage and eject the lowermost blanks of each stack individually from said chamber in a predetermined 90 timed relation.

3. In a blank heating furnace, a combustion chamber provided with an inclined surface and a burner, means to guide a 100 series of blanks along said inclined surface arranged and contacting with the body portions of said blanks to allow the same to have only their portions to be worked exposed to the flame of said burner, and means for automatically successively engaging and discharging the blank of highest temperature from said guiding means.

4. In a blank heating furnace, a combustion chamber, means for guiding a series of blanks through said chamber, said means 110 having surfaces contacting with said blanks to cover a substantial portion thereof but to have the portions to be worked projecting into said chamber, and power operated means for discharging the blanks from said 115 chamber.

5. In a blank heating furnace, a combustion chamber, spaced inclined blank guides formed therein each being adapted to receive a stack of blanks, burners disposed between 120 said guides and discharging in a direction away therefrom, said blanks being exposed to direct radiation in said combustion chamber, and means to automatically engage and discharge the blanks individually from said 125 chamber.

6. A blank heating furnace comprising a heating chamber, means for feeding a stack of superimposed blanks thereto by gravity, and means for successively engaging and 130

discharging the lowermost blanks of said stack individually from said chamber including a plunger reciprocable in an inclined plane.

5 7. In a blank heating furnace, a heating chamber, means for guiding a series of blanks through said chamber, said means having surfaces contacting with said blanks to cover a substantial portion thereof and 10 have only the portions to be worked projecting into said chamber, and means for successively engaging and discharging the blanks individually from said stack.

8. In a blank heating furnace, a heating 15 chamber, means for guiding a series of blanks through said chamber, said means having surfaces contacting with said blanks to cover a substantial portion thereof and have only the portions to be worked project-

ing into said chamber, and means comprising 20 a reciprocable plunger engageable with certain of the blanks to individually eject the same which have been longest subjected to the heat of said chamber therefrom.

9. A blank heating furnace comprising a 25 heating chamber adapted to receive a series of blanks, means for individually ejecting the blanks from said chamber comprising a reciprocable plunger engageable with certain of the same, and means for feeding a 30 stack of superimposed blanks to said ejecting means by gravity, said latter means comprising an inclined blank receiving guide-way disposed substantially perpendicular to the line of reciprocation of said plunger. 35

In testimony whereof I affix my signature.

SVEN T. NELSON.
